Albert E. Deitrich
ATTORNEY

UNITED STATES PATENT OFFICE.

AMEL RICHTER, OF EL CENTRO, CALIFORNIA.

HAME HOOK.

Application filed July 18, 1925. Serial No. 44,539.

The invention has for its object to provide a simple and inexpensively constructed hame hook efficient in use and which may be quickly and easily applied to or removed from use.

5 My hook comprises a pair of plates hingedly connected and provided with bayonet slots a portion of which register to receive the trace ring and which bayonet slots are 10 of varied lengths whereby when the trace ring has been affixed to position the slots will overlap to lock the same to such position against inadvertent removal.

15 Other objects and advantages of the invention will be apparent by reference to the following detailed description and the claims appended thereto, reference also being had to the accompanying drawing, in which:—

20 Figure 1 is a detail perspective view of the invention, the manner of application of the trace ring being shown.

Figure 2 is a side elevation of the hame hook mounted for use.

25 Figure 3 is an edge view of the hame hook.

30 My improved hame hook is constructed to comprise two simple spring metal plates hinged together and suitably slotted for the purpose of receiving and securing the trace-ring.

35 The first plate is designated 1 and as stated is constructed of relatively thin spring metal of a width permitting of the ready slipping of the same through a hame staple 2 of a hame, a portion of which is indicated by the numeral 3.

40 The second or opposing plate 4 is constructed of the same material and of the same width as plate 1.

45 Plate 1 is turned back upon itself at one end, as at 5, to form a spring roll providing a substantially ovate pocket 6 suitable for freely receiving the hame staple 2, and in such manner as to cause the bent down edge 7 to tend to impinge upon the edge of the plate 4 which is adapted to be slipped thereunder a short distance.

50 The edge of the plate 4 adapted to fit under the edge 7 is provided with extensions which are bent upon themselves to provide hinge tongues 8 adapted to cooperate with the hinge slots 9 formed in said edge 7 in providing for hinged connection of the plates 1 and 4.

55 By constructing the plates of relatively

thin spring metal and with the spring roll 5 it is possible to quickly mount the hook by inserting the plate 1 through a hame staple 2 and moving the parts relatively to bring the said staple into the socket 6. The spring 60 roll 5 will permit the hinge connections to move out and let the staple pass.

Each of the plates 1 and 4 is provided with a bayonet slot having equal length cross legs and varied length longitudinal legs. 65

The longitudinal or varied length slots 10 oppose each other or are in register at their front ends but by reason of the variance of their lengths the rear portion of the one provided in plate 1 is covered over by plate 4. 70 This effects an off-register positioning of the equal length cross legs 11 closing both such cross legs when the plates are in flatly opposed relation, see Figure 2, but permits of a bringing into register of the cross legs 75 11 when the plates are moved to the position indicated in Figure 1.

As will be observed by reference to Figures 1 and 2 when it is desired to secure a 80 trace to the hame hook the plates are separated to the position indicated in Figure 1 when the trace-ring may readily be inserted through both cross legs 11 into the longitudinal legs 10. When the plates are closed to the position indicated in Figures 2 and 3 85 the trace ring will be lock-secured in the fore parts of the legs 10.

Not only will the pull on the trace tend to secure the plates 1 and 4 in close opposed relation but the impinging action of the 90 edge 7 will also aid such action.

While I have disclosed both cross legs 11 as cut from the same edges I consider that the forming thereof in opposite edges would come within the scope of my invention. 95

From the foregoing description, taken in connection with the accompanying drawing, it is thought the novel details of construction, the manner of use and the advantages of my invention will be readily apparent to 100 those skilled in the art to which it relates.

What I claim is:—

1. A hame hook comprising a pair of hinged plates each having a slot therein, said slots each being directed in the same general 105 direction as the other, one of said slots being shorter than the other, said slots having portions in register when the plates are in contact and other portions out of register when the plates are in contact, said other 110

portions being adapted to be brought into cooperative register when the plates are moved apart on their hinge connection, all being arranged whereby when the plates are 5 in contact and a ring is in position in the registered parts of the slots it will have bearing against both plates at the front edges of the slots opposite the hinge, whereby pull on the ring will tend to hold the 10 plates in contact substantially as shown and described.

2. A hame hook comprising a pair of hinged plates each having a bayonet slot cooperative in receiving and securing a tracing ring, one plate having an end thereof bent back upon itself to form a spring roll forming a hame staple receiving pocket and presenting the said bent end in position for impinging upon the end of the other plate,

and hinge connections between the impinging and impinged plate ends. 20

3. A hame hook comprising a pair of hinged plates each having a bayonet slot therein, portions of the longitudinal parts of such slots being in register, and the cross parts of such slots being out of register when the plates are opposed but which may be brought into cooperative register by movement of the plates on their hinge connection, one plate having an end thereof bent back 25 upon itself to form a spring roll forming a hame staple receiving pocket and presenting the said bent end in position for impinging upon the end of the other plate, and hinge connections between the impinging 30 and impinged plate ends. 35

AMEL RICHTER.
